UNITED STATES PATENT OFFICE

AMOS E. NORTHUP, OF DETROIT, MICHIGAN, ASSIGNOR TO REO MOTOR CAR COMPANY, A CORPORATION OF MICHIGAN

DESIGN FOR A HOOD, RADIATOR, AND FENDER ASSEMBLAGE FOR AUTOMOBILES

Application filed February 28, 1931, Serial No. 38,862. Term of patent 7 years.

To all whom it may concern:

Be it known that I, Amos E. NORTHUP, a citizen of the United States, residing at Detroit, in the county of Wayne and State of Michigan, have invented a new, original, and ornamental Design for Hood, Radiator, and Fender Assemblage for Automobiles, of which the following is a specification, reference being had to the accompanying drawings, forming a part thereof.

Fig. 1 is a front elevational view of a hood,

radiator and fender assemblage showing my new design.

Fig. 2 is a side elevational view, and

Fig. 3 is a front perspective view of the design.

I claim:

The ornamental design for hood, radiator and fender assemblage for automobiles, as shown.

AMOS E. NORTHUP.
